United States Patent Office

Des. 196,378
Patented Sept. 24, 1963

196,378

HOSTESS TRAY OR THE LIKE

Manuel S. Ziskin, Mayfield Heights, and Harold O. Wagner, Sheffield Lake, Ohio, assignors to Kromex Corporation, Cleveland, Ohio, a corporation of Ohio

Filed Jan. 10, 1963, Ser. No. 73,138

Term of patent 14 years

(Cl. D44—10)

Fig. 1

Fig. 2

Fig. 3

FIG. 1 is a perspective view of a hostess tray or the like showing our new design;

FIG. 2 is a side elevational view; and

FIG. 3 is a top plan view thereof.

The essential features of the design are shown in full lines, with details of the tray configuration being omitted for convenience of illustration.

We claim:

The ornamental design for a hostess tray or the like, substantially as shown and described.
